UNITED STATES PATENT OFFICE.

AUGUST EIMER, OF NEW YORK, N. Y.

ELECTRICAL FURNACE.

1,197,275.

Specification of Letters Patent. Patented Sept. 5, 1916.

Application filed July 18, 1914. Serial No. 851,703.

To all whom it may concern:

Be it known that I, AUGUST EIMER, a citizen of the United States, and resident of the borough of Manhattan, in the city, county, and State of New York, have invented certain new and useful Improvements in Electrical Furnaces, of which the following is a specification.

This invention relates to electric furnaces or muffles and my improvements are directed to means whereby the heating surfaces of said devices may comprise multiple heating units each separately reversible, and whereby each heating unit may be adapted for reversal in its operative arrangement, to present on one side exposed heating conductors sunk in grooves and directed toward the furnace interior, and when reversed to present to the furnace interior a smooth, unbroken surface completely covering the heating conductor.

The material of which the heating units are formed is of such a character as to withstand the action of heat and at the same time has the property of conducting heat, to readily communicate the heat it receives to the furnace interior; also being a non-conductor of electricity, to insulate the conductor lengths which are spaced apart in said heating units. As examples of such material I may refer to fused, semi-fused and calcined alumina, magnesia and zirconia, silica, porcelain and quartz.

The heating units, which are adapted to protectingly contain the electrical conductors, are so constructed that they fit removably together to form the inclosing interior walls of the muffle or furnace, in such manner that any one or all of the unit plates forming the sides, top and bottom thereof, may conveniently be removed and reversed, thereby providing for the instant adaption of the furnace or muffle for any desired character of work. The heating members or plates, which have parallel, sunken grooves in one surface to contain a conductor in non-extruding relation, have alternate opposite end portions recessed to contain the looping portion of the conductor in turning into the next adjacent grooves, to prevent extrusion of said conductor at the ends of the heating member.

Other objects and features of my invention will appear in the following description.

In the drawing accompanying the application, Figure 1 is a front sectional view of

one form of my improved furnace or muffle showing the side, top and bottom reversible heating units and their manner of removable placement. Fig. 2 is a similar view of a furnace with arched top removable or swinging open upon a hinge, the top portion having means supporting the upper heating unit independently of the lower portion of the furnace. Fig. 3 is a similar view of a furnace corresponding to that shown in Fig. 2 excepting that the span of the upper section is of greater extent than the span of the lower section to contain the increased girth of vessels like crucibles which have a greater diameter at the top than at the bottom. Fig. 4 is a similar view of a furnace provided with heating sections at each of its six sides. Fig. 5 is a detail plan view of a heating member. Fig. 6 is a fragmentary side elevation to show binding posts for the conductor terminals, and Fig. 7 is a section through the front cover for the furnace shown in Fig. 1.

Referring first to that form of my invention shown in Fig. 1 the housing of the furnace will be seen to consist of the side walls 1, end 2, top 3, base 4, and removable front cover 5, (Fig. 7). This housing is composed of suitable material of low thermal conductivity, which will conserve the heat generated within the furnace and retard its convection. The base heating member 7 has its opposite side portions 8 reduced, by recessing them on both surfaces. The side heating members 9 are rectangular in cross section and stand vertically upon the reduced portions of the base heating member 7, and the upper heating member 10 has reduced side portions 11 which fit upon the tops of members 9 to support said member 10.

The side walls 1 of the furnace are notched longitudinally at their upper portions, as at 12, and at their lower portions, as at 13, to respectively receive the projecting ends of the upper and lower heating members. It will be observed that said upper and lower heating members are interchangeable, and are also reversible, the same being true of the opposite side heating members. Further that the side heating members may be removed without disturbing the upper heating member, which, without their support, remains lodged in the notches 12. Obviously the lower notches 13 render possible the interchangeable character of the upper and lower heating members.

Each heating member is provided on one

surface with a series of parallel grooves 14 for a resistance conductor, which may be in form of a spiral wire, or of other desirable character. These grooves have relatively 5 narrow entrance slots to prevent extrusion of the conductor, and the divisional walls between adjacent grooves are successively shortened at opposite ends, as at 15, to allow the conductor to turn from one groove 10 end into the next groove to avoid exposing the conductor beyond the end of the heating member. The opposite terminals from each heating member may be passed through orifices in the rear wall of the furnace and 15 there connected in any desired series or parallel electrical arrangement, as to binding posts 16.

When the heating members are arranged in the furnace in the manner shown in Fig. 20 1 with their open groove surfaces facing inwardly the furnace will be useful for certain purposes as where quicker heat is required, or one or more of said heating members may be so placed and the other members 25 arranged with their opposite or closed smooth surfaces facing inwardly, or, if desired, all the heating members may be reversed to present to the furnace interior the closed smooth surfaces of all the heating 30 members.

It will be readily understood, in the great variety of uses to which the heat of the furnace may be applied, that the ability to promptly transform the heating members, 35 or some of them, by reversal from exposed conductor heaters to plain heater walls, and vice versa, largely extends the range of usefulness of the furnace. A particular instance where it is undesirable to present exposed conductors to the furnace is where the material being heated evolves fumes deleterious in their action upon the conductors; further where directly radiated heat would 40 prove injurious to fine edged steel cutting 45 tools.

In Fig. 2 is shown an example of my improved furnace wherein the housing 17 is provided with an arched cover 18, which may be hinged to said housing, as at 19. 50 The arched cover 18 is provided with an annular flange 20, detachably connected thereto, at its base, and extending inwardly beyond the inner perimeter of said base, to support a concavo-convex heating member 55 21. The member 21 not being reversible must be constructed specially with either exposed or covered conductors.

The furnace shown in Fig. 3 may correspond in all essentials with that just described excepting that the maximum transverse interior area of its heating member 22 may exceed the transverse area of the heat-

ing member 23 in the housing, which it 65 closes, in that manner accommodating a vessel whose upper portion is larger in girth than its lower portion, without leaving a greater clearance between the heating members and the vessel than is necessary, thereby permitting the heating surfaces to be 70 equally effective over all portions of the vessel whose contents are being heated, which vessel may be a crucible.

In Fig. 4 I have shown a furnace in rectangular form, whose four walls are provided with heating members 24, also having 75 a base heating member 25 and an upper heating member 26, which may be removed independently or with the top 27, the forward wall and heating member however not appearing in the front sectional view 80 shown.

Variations may be made within the spirit and scope of the invention, and parts thereof may be used without others.

I claim:

1. A furnace or muffle provided with electrical heating, reversible members in opposed spaced relation therein, said members each having a series of parallel exposed grooves on one side to contain a resistance conductor, with inset notches alternating at opposite ends between adjacent grooves to carry the conductor from one groove to another, the opposite side of said members provided with a smooth, conductor covering 95 heating surface, and said members having interlocking edges for their engagement when said members are arranged with either surface presented to the furnace interior.

2. A furnace or muffle provided with electrical heating members in opposed, spaced relation therein, said members being reversible to present either surface thereof to the furnace interior, and said members having interlocking edges for their engagement 100 when said members are arranged with either surface presented to the furnace interior.

3. A furnace or muffle provided with interchangeable, electrical heating members in opposed spaced relation therein, said members being reversible to present either surface thereof to the furnace interior, and said members having interlocking edges for their engagement 110 when said members are arranged with either surface presented to the furnace interior.

Signed at the borough of Manhattan in the city, county and State of New York this 16th day of May A. D. 1914.

AUGUST EIMER.
